UNITED STATES PATENT OFFICE

134,182

DESIGN FOR AN AIRPLANE

Frank A. Wagner, St. Paul, Minn.

Application June 24, 1941, Serial No. 101,649

Term of patent 3½ years

To all whom it may concern:

Be it known that I, Frank A. Wagner, a citizen of the United States, residing at Saint Paul, in the county of Ramsey and State of Minnesota, have invented a new, original, and ornamental Design for an Airplane, of which the following is a specification, reference being had to the accompanying drawing, forming part thereof.

Figure 1 is a top plan view of an airplane showing my new design.

Figures 2, 3 and 4, are side elevational, bottom plan, and front elevational views, respectively, and showing the airplane with the landing gear in the retracted position as it appears when in flight.

I claim:

The ornamental design for an airplane, as shown.

FRANK A. WAGNER.
